UNITED STATES PATENT OFFICE.

JOSEPH I. VAN TOCHINE, OF FORT WAYNE, INDIANA.

COLLAR ATTACHMENT.

1,147,577.

Specification of Letters Patent. Patented July 20, 1915.

Application filed May 16, 1913. Serial No. 768,118.

To all whom it may concern:

Be it known that I, JOSEPH I. VAN TOCHINE, a citizen of the United States, residing at Fort Wayne, in the county of 5 Allen and State of Indiana, have invented new and useful Improvements in Collar Attachments, of which the following is a specification.

This invention relates to collar attachments; and it has for its primary object the provision of identical devices for receiving the marginal edges of the outer fold of the collar at the corners thereof, and the construction of said devices whereby they may 10 be made of a material selected with a view to harmonizing with a particular color scheme of a dress, shirt or other apparel and thereby add to the attractiveness and dressy appearance of the collar.

20 A further object of the invention is the provision of means for facilitating the operation of applying the devices to or removing the same from the collar.

Another object of the invention is the provision of means for holding the devices against accidental displacement from the collar while the latter is worn.

With these and other objects in view, the invention consists of certain novel features 30 of construction, combination and arrangement of parts, as will be hereinafter described and claimed.

In the accompanying drawings:—Figure 1 is a perspective view of a collar, showing 35 the application of the device thereto; Fig. 2 is a similar view, showing a slight modification of the device; Fig. 3 is a similar view, showing a further modification; Fig. 4 is a similar view, showing a slightly further modified form of the device; Fig. 5 is a similar view, showing a still further modified form of the device; Fig. 6 is a similar view, showing a further modification of the device; Fig. 7 is a section on line 7—7 of Fig. 4; Fig. 8 is a perspective view of the device shown in Fig. 1 detached from the collar; and Fig. 9 is a perspective view of the device shown in Fig. 2 detached from the collar.

The attachment illustrated in Figs. 1 and 50 8 of the drawings comprises identical devices 1 which may be constructed of metal, such as sheet gold, silver or the like, celluloid, rubber or any other well known composition of matter which may be found most desirable for the purpose. The metal form-

ing each device is folded on itself so as to provide inner and outer surfaces or walls 2 and 3 which are connected with each other by a curved wall 4 which serves to space the walls 2 and 3 from each other so as to provide an intervening channel or space 5 therebetween for the reception of the edges of the collar at the corners thereof. The device as applied to the outer fold of the collar as shown in Fig. 1 includes a relatively long 60 leg 6 which extends partly around the lower edge of the fold of the collar and an upwardly curved leg 7 which extends along the vertical edge of the outer fold of the collar, as shown. In describing this arrangement 65 of the different legs of the device it is stated that various modifications in such arrangement may be resorted to as may depend upon the shape and style of the collar. The device is intended to be retained in operative 70 position upon the collar through the frictional contact of the walls 2 and 3 against the opposite sides of the outer fold of the collar. However with a view to increasing 75 the friction between the collar and the device the inner wall 3 may have stamped therefrom suitable substantially V-spurs 8 which extend normally into the channel or collar receiving space 5, so as to be advanced 80 against the collar, as will be understood.

85 In the form of the device shown in Figs. 2 and 9, the attachment comprises identical devices 10 each including a horizontal leg 11 and a vertical leg 12, the wall 13 of the latter being connected with the wall 14 of the former through a diagonal bar 15.

The attachment shown in Fig. 4 comprises identical devices 16 each having a relatively long leg 17 and a short leg 18, the latter being arranged at an angle to the former and associated therewith so that both legs are designed for the effective reception of the edges of the outer fold of the collar at the extreme corner of the latter. In this form of the invention each of the 95 legs 17 and 18 is provided with walls 19 and 20 of varying widths, the latter being relatively narrow as compared with the width of the former so that the former will serve as a guide in the initial application of the 100 device to the corner of the collar.

105 The attachment shown in the remaining modifications are identical with those previously described, the difference being only in the relative association of the companion 110

legs of the device or the particular arrangement of the legs so as to adapt themselves to a collar of a given design.

While the attachment is designed primarily as means which will lend admirably to the attractiveness of the collar at the extreme points thereof it is also described that the application of the attachment to the points will materially strengthen the collar and prevent the same from breaking down at the corners, while it is further described that the companion devices of the attachment are provided at the immediate points of connection of the different legs of the devices with each other with curved relatively broad surfaces 21 which completely house the corners or points of the collar so as to prevent said points from tearing or wearing the shirt of the wearer at such places upon the shirt where the points of the collar usually rest and rub thereagainst.

While the attachment is only shown as applied to collars it is obviously understood that the same may be applied to cuffs or any other portions of a garment that may be found appropriate.

The devices in the various modifications may be provided with any external orna-

mentation such as engravings upon the outer walls or exposed portions of the devices, as will be understood.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention, as claimed.

Having thus described my invention, what I claim is:

A collar attachment comprising a channel member attached on the lower edge of a turned down collar and having one of its walls provided with struck up V-shaped spurs to engage the collar and secure the attachment thereto.

In testimony whereof I affix my signature in presence of two witnesses.

JOSEPH I. VAN TOCHINE.
